(57) **CLAIM**

The ornamental design for a tongue and groove system, as
shown and described.

DESCRIPTION

FIG. 1 is a side view of the tongue and groove system with
the tongue and groove together.

FIG. 2 is a side view of the tongue and groove system with
the tongue and groove apart.

FIG. 3 is a side perspective view showing the tongue of the
tongue and groove system.

FIG. 4 is a side perspective view showing the groove of the
tongue and groove system; and,

FIG. 5 is a side perspective view of the tongue and groove
system with the tongue and groove apart.

The present application is directed to the design illustrated
in the drawings. The broken line portions of the disclosure
are for illustrative purposes only and form no part of the
claimed design.
